UNITED STATES PATENT OFFICE.

ROBERT D. BRUCE, OF PITTSBURGH, PENNSYLVANIA.

DESIGN FOR AN AIR-NAVIGATING VESSEL.

45,550.

Specification for Design.

Patented Apr. 7, 1914.

Application filed November 15, 1913. Serial No. 801,262. Term of patent 14 years.

To all whom it may concern:

Be it known that I, ROBERT D. BRUCE, a citizen of the United States, residing at Pittsburgh, in the county of Allegheny and State of Pennsylvania, have invented a new, original, and ornamental Design for Air-Navigating Vessels, of which the following is a specification, reference being had to the accompanying drawing, forming part thereof.

Figure 1 is a plan view of the vessel. Fig.

2 is a view in side elevation. Fig. 3 is a view in front elevation. Fig. 4 is a view in rear elevation.

I claim:

The ornamental design for an air navigating vessel, as shown.

ROBERT D. BRUCE.

Witnesses:

C. M. CLARKE,
FREDK. STAUB.
